UNITED STATES PATENT OFFICE.

ALLE S. HAMILTON, OF LOS ANGELES, CALIFORNIA.

CUT-OUT VALVE FOR MUFFLERS.

No. 841,392.

Specification of Letters Patent.

Patented Jan. 15, 1907.

Application filed July 17, 1906. Serial No. 326,570.

To all whom it may concern:

Be it known that I, ALLE S. HAMILTON, a citizen of the United States, residing at Los Angeles, in the county of Los Angeles and State of California, have invented new and useful Improvements in Cut-Out Valves for Mufflers, of which the following is a specification.

In the operation of motor-cycles it is desirable to have the motor exhaust directly into the open air; but in cities where it is against the law to operate motor-cycles without a muffler being applied to the exhaust I have found it desirable to have a cut-out valve, so as to control the direction of the exhaust. By means of this valve the direction of the exhaust can be instantly controlled.

By opening and closing the valve the explosions of the motor can be utilized as an alarm-signal. When passing along roads in the open country, where the explosions of the engine are not objectionable, it can be widely opened, thereby increasing the efficiency of the engine.

My invention relates to cut-out valves for exhaust-pipes of gasoline or other engines where a muffler is used; and the object thereof is to provide a valve that is economical in construction, efficient in operation, and by means of which the exhaust may be directed through the muffler when desired. I accomplish this object by means of the device described herein and illustrated in the accompanying drawings, in which—

Figure 1 is a longitudinal section of the outer end of an engine exhaust-pipe and muffler with my valve in place thereon. Fig. 2 is a front elevation of the exhaust-pipe and muffler secured thereto with the valve in an open position, the dotted lines indicating its position when closed.

Referring to the drawings, 5 is the outer end of an engine exhaust-pipe having a plurality of perforations 6 in its outer end. Rigidly secured upon the outer end of the exhaust-pipe is a muffler 7 of any preferred construction. Upon the outer end of the exhaust-pipe and in screw-threaded engagement therewith is a valve-seat 8, to whose outer face 9 is pivotally secured gate 10. This valve-gate is preferably flat and is pivotally secured and held to the valve-seat 9 by a screw 11. Its outer edge is provided with a radial guide-slot 12, through which passes a

screw 13, which is secured to the valve-seat 8. Projecting outwardly from the periphery of the valve-gate 10 is a lug 14, to which is pivotally connected an operating-rod 15. The valve-gate 10 is held in its open or closed position by means of a coiled spring 16, one end of which is secured to a post 17, rigidly secured to valve-seat 8, the other end being secured to a post 18, rigidly secured to the valve-gate 10 at a point so that it will hold the gate in its open or closed position.

Having described my invention, what I claim as new, and desire to secure by Letters Patent, is—

1. A cut-out valve comprising a valve-seat having a centrally-disposed aperture therein adapted to be secured to an engine exhaust-pipe; a gate pivotally secured to and at one side of the opening in said valve-seat; retaining means secured to said valve and gate whereby the gate is held in its fully-open or completely-closed position; and means to control the movement of said gate.

2. A cut-out valve, comprising a valve-seat having a centrally-disposed aperture therein adapted to be secured to an engine exhaust-pipe; a gate pivotally secured to and at one side of the opening in said valve-seat; a coiled spring having its ends secured to said valve and gate whereby the gate is held in its fully-open or completely-closed position; and means to control the movement of said gate.

3. A cut-out valve, comprising a portable valve-seat having a centrally-disposed aperture therein adapted to be secured to the outer end of an engine exhaust-pipe; a valve-gate having a radial slot in its outer edge adapted to engage a pin on the valve-seat, said valve-gate being pivotally secured to and at one side of the opening in said valve-seat; a coiled spring having its end secured to the valve-seat and to the valve-gate, whereby the valve-gate is held in its fully-open or completely-closed position; and means to control the movement of the gate.

In witness that I claim the foregoing I have hereunto subscribed my name this 15th day of June, 1906.

ALLE S. HAMILTON.
